BY HIS ATTORNEY.

James F. Williamson

UNITED STATES PATENT OFFICE.

THOMAS THOMPSON, OF MAKOTI, NORTH DAKOTA.

LOCK.

1,411,314.

Specification of Letters Patent.

Patented Apr. 4, 1922.

Application filed April 25, 1921. Serial No. 464,293.

To all whom it may concern:

Be it known that I, THOMAS THOMPSON, a citizen of the United States, residing at Makoti, in the county of Ward and State of North Dakota, have invented certain new and useful Improvements in Locks; and I do hereby declare the following to be a full, clear, and exact description of the invention, such as will enable others skilled in the art 10 to which it appertains to make and use the same.

This invention relates to a lock and the invention is shown as applied to different forms of locks. The invention herein disclosed is an improvement upon that disclosed and claimed in my previously granted Patent No. 1,311,102, granted July 22nd, 1919.

It is an object of this invention to simplify 20 the construction shown in said patent and improve the same by forming the operating bar or outer member of the lock with an integral head which, when the lock is closed, will cover the keeper and portion of the 25 latch engaging the same.

It is also an object of the invention to provide the latch and the sides of the enclosing casing with inter-engaging portions forming a locking means which, when the 30 lock is closed, will form one continuous surface.

It is still another object of the invention to so construct the lock that the same can be used as a locking or disengaging link of a 35 chain.

These and other objects of the invention will appear from the following description made in connection with the accompanying drawings, in which like reference characters 40 refer to the same parts in the different views thereof, and in which—

Fig. 1 is a plan view of one form of a lock;

Fig. 2 is a view in side elevation of the 45 same partly in section, showing the lock partially open;

Fig. 3 is a view in side elevation showing the lock in the form of a chain link, the parts being shown in different position in 50 dotted lines;

Fig. 4 is a section on the line 4—4 of Fig. 3 looking in the direction of the arrows;

Fig. 5 is a section on the line 5—5 of Fig. 3, looking in the direction of the arrows; and

Fig. 6 is a side view of the latch member used in the structure of Fig. 3.

Referring to the drawings, particularly to Figs. 1 and 2, two movable parts 1 and 2 are shown which may represent portions of the door and door casing or any other movable parts which it is desired to lock together. The keeper member is shown as 3 provided with a flange and an upwardly inclined lip portion 3^a, this keeper being secured to the member 1 by suitable nutted bolts passing through holes in the flange thereof. The latch portion of the lock comprises a casing 4 having a flange extending therefrom alining with the flange on the keeper 3, which flange is also adapted to be 70 secured to the member 2 by nutted bolts passing through openings therein. The casing 4 has spaced side portions 4^a extending upwardly from the flange thereof and a bar 5 is provided with spaced rib members 75 5^a on the under or inner side thereof by means of which it is pivoted to the side portions 4^a of the casing by a suitably riveted or headed pivot member. The member 5 has its end adjacent the pivot bent downwardly so that when it is in closed position it will aline with the ends of the members 4^a and form a closed casing. A latch member 6 is pivoted to the bar 5 by spaced ribs 6^a through which and the ribs 5^a, the pivot 80 7, suitably riveted or otherwise secured, extends. This pivot 7 is located below the pivot connecting the bar 5 to the casing so that the same bears an eccentric relation thereto. The latch member 6 extends forwardly and is adapted to seat over the portion 3^a of the keeper, the front end of the latch being bent or formed with a downwardly curved portion adapted to contact and slide on the flange of the keeper 3. The 85 latch also comprises at its front end the side walls 6^c extending continuous with the front portion thereof, which walls are formed with a projecting portion at the rear sides thereof, the end of which is formed as a point or 90 V-shaped projection 6^b. The front end of the side portions 4^a are formed with a notch of the same shape as the projection 6^b and adapted to receive the same when the lock 95 is closed. The front portion of said projection on the latch is formed with an inclined edge. The bar 5 is also formed at its front end with downwardly extending side portions 5^b which extend continuous with the front portion which is curved 100 downwardly and the lower edge of the same, as well as the edge of the side por-

105
110

tions are adapted to engage with the flange 3 of the keeper. The rear edge of the side portions 5^b are formed on an incline adapted to engage when the lock is closed with the incline on the front edge of the projection on the latch. The extreme rear end of the side portions 5^b are formed of rectangular shape and the said ends are adapted to engage with the end of the casing 4 when the lock is closed. It will thus be seen that when the lock is in closed position, the outer surfaces of the side portions 5^b, the projections having the point 6^b and the sides 4^a of the casing will all lie flush or in the same plane and the side of the lock will present a continuous surface.

In order to lock the bar 5 so that the same cannot be lifted when the lock is closed, the same is provided with a pivoted button 8 of oblong shape having a stem with a projecting shoulder 8^a by which it is secured to the inner surface of the bar 5 by shouldered plates 9 riveted to said bar. The said stem extends through the bar 5 and is formed with a keyhole to receive a key by which the same may be turned. When the bar 5 is moved to closed position the button 9 will pass through a slot 10 formed in the top of the latch 6 and when said button is turned, the ends thereof will engage under the top of the member 10 at the sides of the slot and will prevent the bar 5 from being lifted.

Owing to the eccentric connection between the latch 6 and bar 5 it will be readily seen that when the bar 5 is raised the latch 6 will be moved outwardly longitudinally, as shown in Fig. 2. The end of the bar 5 also projects under the lugs 6^a so that continued upward movement of the bar 5 will swing the latch 6 upwardly about its pivot to disengage the same from the keeper.

In Figs. 3 and 6, the lock is shown formed as a link of a chain and in these figures the casing 11 comprises a plate formed in substantially U-shape, one end thereof being rounded and provided with an aperture 12 to receive the succeeding link of the chain. A bar 13 corresponding to the bar 5 is pivoted by a suitable pivot 14 between the sides of casing 11. It will be noted that the front end of the casing 11 is slightly inclined and one side thereof is provided with a V-shaped notch 11^a. In its front end, the bar 13 is formed with depending parallel sides 13^a through which a hook-forming slot 15 extends. The rear edges of the sides 13^a are formed on a similar angle to the front sides of the casing 11 and are adapted to approximately engage therewith. A latch member 16 formed with a hook shaped front end is pivoted to the bar 5 by a suitable pivot 17. This latch slides between the bar 5 and one side of the casing 11 and has a projecting triangular or V-shaped lug 16^a thereon which, when the lock or link is closed is

adapted to engage in the notch 11^a, as shown in Fig. 3. It will be seen that when the link is closed the outer surfaces of the sides 13^a and 11 as well as the lock 11^a, all lie in the same plane or flush with each other. Owing to the eccentric connection between the bar 13 and the latch 16 when the said bar is lifted to a position shown in dotted lines in Fig. 3, the latch member will be moved longitudinally. The link will then be in open position and a pivot or portion of the succeeding link can be placed in the hook portion of the latch. The link will then be closed and the slot 15 will move down over the pivot or portion of the chain link engaged in the hook and the same will be firmly held by the headed portion of the bar 13 and the latch 16. When the link is closed it will be seen that the same cannot be opened by longitudinal stress placed on the links.

The form of lock shown in Figs. 1 and 2 can be used on doors of various kinds or on trunks, suit cases, or grips. The said lock when closed forms a neat and compact enclosed structure. The link shown in Figs. 3 and 6 also forms a smooth compact structure when closed and which can also be quickly and easily opened when it is desired to disengage the same.

It will, of course, be understood that various changes may be made in the form, details and arrangement of the parts without departing from the scope of applicant's invention, which, generally stated, consists in the matter shown and described and set forth in the appended claims.

What is claimed is:

1. A device of the class described having in combination a latch adapted to engage over a member to be held and a pivoted bar to which said latch is eccentrically pivoted adapted to operate said latch, said bar being formed at its free end with a head portion adapted to enclose the end of said latch.

2. A lock having in combination a latch adapted to engage over a member to be held, a pivoted member to which said latch is eccentrically pivoted adapted to operate said latch, a casing enclosing said latch and member, inter-engaging means on said latch and casing and said bar being formed with a head portion at one end adapted to enclose the end of said latch.

3. A lock device having in combination a casing having substantially parallel sides, a bar pivoted therein, a latch eccentrically pivoted to said bar, said bar being formed with a head having substantially parallel sides enclosing the end of said latch.

4. The structure set forth in claim 3, the sides of the said casing and head portion of said bar having their outer surfaces flush.

5. The structure set forth in claim 3, one of the sides of said casing having a notch in its front end, and said latch having a lug

- formed thereon adapted to engage with said notch in the casing.
6. The structure set forth in claim 5, the outer surface of the casing, the head on said bar, and the lug on said latch, all lying in the same plane.
7. A lock comprising a casing having substantially parallel sides, a bar pivoted therein, a latch disposed in said casing and eccentrically pivoted to said bar, said latch having its front portion formed as a hook, and said bar having its front portion formed as a head adapted to enclose the front end of said latch, said head portion being formed as a hook and adapted to co-operate with the hook portion of the latch.
8. The structure set forth in claim 7, said casing and said latch being formed with inter-engaging means.
9. The structure set forth in claim 7, the front edge of the casing having a notch therein, and said latch having a projecting lug thereon adapted to fit in and engage said notch.
10. A lock device having in combination a casing, a latch pivoted therein and adapted to project therefrom for swinging and longitudinal movement and engage over a member to be held, and interlocking means on said latch and said casing.
11. A lock device having in combination a casing, a latch pivoted therein and adapted to swing and be moved longitudinally to engage over a keeper, and interlocking means on said latch and casing adapted to engage by the longitudinal movement of said latch.
12. The structure set forth in claim 10, and means connected to the casing for operating said latch.
13. The structure set forth in claim 12, said means being pivoted to said latch and to said casing.
14. A lock device having in combination a casing, a keeper having an upwardly inclined lip, a latch in said casing pivoted for swinging and longitudinal movement and constructed and arranged to project from said casing to engage over said keeper and under the lip thereof, and means pivoted to said latch and said casing for swinging said latch and moving the same longitudinally whereby it is movable over said keeper and moved to engage under the lip thereof.

In testimony whereof I affix my signature.

THOMAS THOMPSON.
